JAMES W. PRICE, OF HENRYETTA, OKLAHOMA, ASSIGNOR OF ONE-HALF TO HETTIE T. MILLER, OF HENRYETTA, OKLAHOMA.

SHADE-ROLLER.

1,319,111.

Specification of Letters Patent.

Patented Oct. 21, 1919.

Application filed February 6, 1919. Serial No. 275,423.

To all whom it may concern:

Be it known that I, JAMES W. PRICE, a citizen of the United States, and a resident of Henryetta, in the county of Okmulgee and 5 State of Oklahoma, have invented certain new and useful Improvements in Shade-Rollers, of which the following is a specification.

My invention is an improvement in shade 10 rollers, and has for its object to provide a cheap and simple roller of the character specified wherein the operation of the spring which rotates the roller to wind up the shade is controlled by a pawl so mounted that it 15 will always be in position to engage the catches of the roller, and which is positively held out of engagement with the catches when the roller is rotating above a predetermined speed, and which may be easily 20 disengaged when desired to adjust the roller.

In the drawings:

Figure 1 is a perspective view of one end 25 of the shade roller;

Fig. 2 is a longitudinal section;

Fig. 3 is an end view of the cap;

Fig. 4 is a top plan view of one end of the 30 roller;

Fig. 5 is a perspective view of the pawl or latch bar.

In the present embodiment of the invention the roller 1, which is of wood, carries the shade 2 which is secured thereto in the usual manner and winds thereon, and one end of the roller is axially cored as indicated 35 at 3, to receive a rod 4 of metal. This rod carries the coil spring 5 which operates the roller, the said spring having one end received in a longitudinally extending notch 6 in the rod, while the other end is adapted 40 to engage the cap 7 on the end of the roller.

This cap, as shown, has a central hub 8 through which the rod extends, and the rod has a collar 9 which engages the end of the hub to hold the rod from outward movement. 45 The outer end of the rod is flattened, as shown at 10, for engagement by a similarly shaped notch in one of the brackets 11 which supports the roller.

The flattened portion 10 of the rod extends 50 from the outer face of the cap to the outer end of the rod and a pawl or latch bar 12 is mounted on this portion of the rod. This pawl or latch bar has a longitudinally extending slot 13 through which the flattened portion of the rod passes, and a plate

14 is arranged on the flattened portion at the outer side of the pawl, the inner face of the plate being convex in the wide dimension of the flattened portion of the rod, that is, from above downwardly when the roller is 60 mounted in the brackets.

Catch lugs 15 are provided on the end of the cap, and the said lugs are adapted to be engaged by either end of the pawl, and the said ends are beveled in opposite directions 65 as indicated at 16, to provide cam surfaces for riding upon other lugs 17, one of which is arranged adjacent to each lug 15 and in front of the same, so that when the pawl is moving in one direction, that is, when the 70 shade is moving upwardly, the ends of the pawl will engage these cams 17, and will be lifted over the catch lugs 15.

When the curtain is moving at a moderate rate of speed, the cam lugs 17 will cause the 75 pawl to over-ride the lugs 15, so that there can be no sticking or stoppage of the curtain until desired. As soon as the speed of the curtain is slowed sufficiently, the pawl will swing into engagement with the catch 80 lugs, it being noted that there is space between each pair of lugs 15 and 17 for this purpose.

Referring to Fig. 5, it will be noted that the ends of the slot 13 are beveled in opposite 85 directions, as indicated at 18, and the beveling is outward from the end of the roller. Thus when the pawl hangs in the position of Fig. 2, the lower end will be swung inward by the beveled end of the slot, to provide a positive engagement between the pawl and the catch lugs. The convex surface of the plate 14 permits this rocking movement of the pawl. In placing the roller in the brackets, the trunnion 10 may be engaged 90 from either edge, since the pawl is reversible, working equally well in either position. The ends of the pawl are similar so that whichever end is downward the engagement between the said end and the catch lugs will 95 take place except when the curtain is moving at a speed sufficient to cause the pawl to over-ride the catch lugs.

The pawl may be released by a slight movement downward, each lug 16 having its 105 face adjacent to the lug 15 beveled to move the pawl outwardly to clear the lug 16, and it is only necessary to turn the roller far enough to cause the engaging end of the latch to move backwardly over the adjacent 110

cam lug to freely release the roller. As soon as the downward pull on the curtain is relaxed, the spring will wind up the roller, and the pawl will swing freely over the catch lugs, being positively lifted over the lugs by the cam lugs.

With the improved curtain, cheap wood may be used, since it is only necessary to core out a small opening. There are but 10 few parts in the catch mechanism, only five including the spring and rod. Hence the device may be very cheaply constructed and, although simple, it is very efficient for the purpose, absolutely preventing sticking 15 of the shade when it is permitted to move up at a fair rate of speed. Slowing of the movement of the shade will permit the pawl to engage, bringing the shade to a halt at the desired point. The manner in which the 20 pawl is hung upon the trunnion insures always a positive engagement of the pawl with the catch lugs.

I claim:

1. In a shade roller, the combination with 25 the roller and the spring for controlling the same, of a pawl, said pawl being mounted to move vertically on the flat trunnion of the shade roller and being supported to swing at its lower end toward the end of the roller, 30 said roller carrying catch lugs at its ends for engagement by the pawl to hold the roller, and the roller having cam lugs adjacent to the catch lugs for lifting the engaging end of the pawl over the catch lugs when the 35 roller is rotating.

2. In a shade roller, the combination with 40 the roller and the spring for controlling the same, of a pawl, said pawl being mounted to move vertically on the flat trunnion of the shade roller and being supported to swing at its lower end toward the end of the roller, 45 said roller carrying catch lugs at its end for engagement by the pawl to hold the roller, said roller having means for lifting the engaging end of the pawl over the catch lugs when the roller is rotating.

3. In a shade roller, the combination with 50 the roller and the spring for controlling the same, of a pawl mounted on the flat trunnion of the shade roller and having means for constraining the same to swing at its lower end toward the roller, said roller carrying catch lugs at its ends for engagement by the pawl to hold the roller against the action

of the spring, and the roller having means 55 adjacent to the catch lugs for lifting the engaging end of the pawl from the catch lugs when the roller is rotated.

4. In a shade roller, the combination with 60 the roller, the spring for controlling the same and the flat trunnion with which one end of the spring is connected, of a pawl mounted to swing on the trunnion and having means in connection therewith for swinging the lower end of the same toward the 65 roller, said means comprising an opening in the pawl through which the trunnion extends, the upper end of the opening being beveled outwardly and upwardly.

5. In a shade roller, the combination with 70 the roller, the spring for controlling the same and the flat trunnion with which one end of the spring is connected, of a pawl mounted to swing on the trunnion and having means in connection therewith for 75 swinging the lower end of the same toward the roller.

6. In a shade roller, the combination with 80 the roller, the spring for controlling the same and the trunnion with which one end of the spring is connected, of a pawl held on the trunnion to swing toward and from the roller, the shade having catch lugs for engagement by the pawl, and having cam lugs for lifting the pawl over the catch lugs when the 85 roller is rotating, and means in connection with the pawl for normally constraining the same to swing toward the curtain.

7. In a shade roller, the combination with 90 the roller, the spring for controlling the same and the trunnion with which one end of the spring is connected, of a pawl held on the trunnion to swing toward and from the roller, the shade having catch lugs for engagement by the pawl, and having cam lugs 95 adjacent to the catch lugs for lifting the pawl over the catch lugs when the roller is rotating.

8. In a shade roller, the combination with 100 the roller and the spring for controlling the same, of a pawl and ratchet mechanism for controlling the winding movement of the roller, and means in connection with said pawl and ratchet mechanism for positively lifting the pawl over the teeth of the ratchet 105 when the roller is moving in a direction to wind the roller above a predetermined speed.

JAMES W. PRICE.
